VAPOR ACTUATED PUMP SYSTEM

Calvin D. MacCracken, Tenafly, N.J., assignor to Jet-Heet, Inc., Englewood, N.J., a corporation of New York

Application March 7, 1957, Serial No. 644,504

7 Claims. (Cl. 60—64)

This invention relates in general to vapor actuated pumping systems and particularly to an improved boiler or vapor pumping system including a heat actuated pump, referred to herein as a thermopump, arranged to both heat and pump water or other liquids.

A thermopump embodied in the pumping system of this invention is generally similar to those disclosed and described in a copending application Serial No. 530,387 filed August 24, 1955, by Nils Erland af Kleen and assigned to the assignee of this application and Patents 2,553,817 issued May 22, 1951, to Nils Erland af Kleen and 2,744,470 issued May 8, 1956, to R. E. Coleman also all assigned to the assignee of this application.

The present invention represents an improvement over those described in the aforementioned application and patents particularly in respect to the construction and arrangement of the parts of the thermopump and its adaptation for pumping water in a boiler system.

A thermopump constructed in accordance with this invention may advantageously use steam available from the boiler itself or from any place in the boiler steam system (such as from the exhaust of apparatus using boiler steam, e.g. main turbines and auxiliary machinery) both to heat and pump water to high temperatures and pressures for use again in the boiler or the boiler system. A pump of this construction is particularly desirable for such uses because it utilizes substantially all the available heat of the steam to both pump and heat the liquid being handled, so that there are substantially no losses in the operation of such a pump. The pump has no appreciable moving parts requiring maintenance, does not use packing or require lubrication, and is substantially noiseless in operation. The pump of this invention may be utilized at any point in a boiler system to heat and pump liquids where there is sufficient activating steam available at temperatures and pressure above that of the liquid being pumped and where the temperature and pressure conditions of the pump actuating steam and the pumping liquid are such that repetitive cyclical condensation of the steam vapor in the pump may be accomplished.

Accordingly it is an object of this invention to provide an improved boiler pumping system.

A further object is to provide an improved liquid pump for a vapor generating system.

A further object is to provide an improved thermopump.

A still further object is to provide a thermally actuated pump which is simple in design, rugged in construction and economical to manufacture.

The various features of novelty which characterize the invention are pointed out with particularity in the claims, annexed to, and forming a part of this specification. For a better understanding of the invention, its operating advantages and specific objects obtained by its use, reference should be had to the accompanying drawings and descriptive matter in which there are illustrated and described several embodiments of the invention.

2

Figure 1 is a schematic view of a boiler system showing a combination thermopump heater actuated by steam bled from one of the stages of the turbine and another thermopump heater actuated by steam from a boiler;

5 Figure 2 is a top plan view of a vapor actuated thermopump heater constructed in accordance with this invention;

Figure 3 is a vertical section taken on the line 3—3 of Figure 2;

10 Figure 4 is a vapor pressure-temperature chart with pressure indicated on logarithmic scale and showing the liquid-vapor curve for water and the pressure step manner of raising water near its boiling point to a high pressure without causing it to boil; and

15 Figure 5 is a schematic view of the arrangement of thermopumps for pumping liquids which are close to their boiling point in the manner indicated in Figure 4.

Referring to Figure 1 of the drawings, the invention as embodied therein comprises a boiler 10 arranged to generate steam and to deliver it to a turbine 12 for utilization therein. The turbine 12 is mounted over a condenser 14. Condensate is pumped from the condenser 14 back to the boiler 10 by means of a conventional condensate pump 16, two thermopump heaters 18 and 20, and a conventional boiler feed pump 22. Make-up feed water is supplied to the system from a reservoir 23 between the condensate pump 16 and the thermopump heater 18. The thermopump heater 18 is actuated by steam from the exhaust of one of the stages of the turbine 12, while the 25 thermopump heater 20 is actuated by steam directly from the boiler 10.

In accordance with the invention each of the thermopump heaters 18 and 20 as shown in Figures 2 and 3 includes a cylindrical outer shell 22 closed by a top cover 35 24 and a bottom plate 26. A cylindrical inner wall 28 extends downwardly from an inner substantially flat top member 29 to a position spaced from the bottom 26, and defines a vapor chamber 30 therein; and, between its outside periphery and the inside of the shell 22, a condenser 32. The vapor chamber 30 and the condenser 32 are in liquid communication at their lower portions.

In some instances, as for example where it is desirable to pump a liquid which may be close to its boiling point, a heat exchanger coil 34 may be advantageously provided in the condenser 32 in order to cool the condenser sufficiently to prevent boiling of the liquid being pumped and possible stopping of the action of the pump. However, a big advantage of the pump is that it wastes substantially no input energy, and, in order that the heat of the system may not be lost in these instances, the heat exchanger coil 34, located in the condenser 32, would be connected to circulate liquids therethrough which require heating before use (such as lube oil or fuel oil, for example). Another way to pump liquids which are close to their boiling points without causing boiling which would stop the operation of the thermopump, would be to connect several pumps together in the manner of Figure 5 as will be described more fully hereinafter.

In accordance with the invention, steam from the boiler 10 or from the exhaust of one of the stages of the turbine 12 (depending on the pressure temperature requirements of suction and discharge of the liquid being pumped) is directed through a conduit 36 to a steam valve 38 through a flow regulator valve 40 and into the top of the vapor chamber 30. The conduit 36 is connected by means of a substantially U-shaped vapor tube 42 to the upper part of the condenser 32. The vapor tube includes an inner leg 42a and an outer leg 42b. The vapor tube 42 extends substantially below the top of the vapor chamber 30 at the lowest portion of the U-bend. The flow regulator 40 is provided to prevent surges of steam therethrough to the thermopump

during pressure fluctuations therein during pumping and is necessary to permit operation of the thermopump with steam tapped from a pressure line.

In many instances (e.g. when the liquid being pumped is near its boiling point) it is desirable to control the rate of steam vapor condensing in the vapor tube 42. This may be done by the use of suitable heat transferring means surrounding the vapor tube 42, as for example, a heat exchanger 44 arranged in heat exchange relationship with the inner leg 42a of the U-shaped tube 42. Where the heat exchanger 44 is utilized it is preferable to circulate a liquid therein which requires heating before use in order to eliminate heat losses in the system. A valve 46 is provided in an inlet conduit 48 to the heat exchanger 44 in order to regulate the amount of liquid being circulated therein as a coolant.

In order to prevent condensation of steam in the vapor chamber 30, an insulated float 50 is arranged to float on the liquid in the vapor chamber and insulate the steam from the liquid. An inlet conduit 52 is connected to the lower portion of the condenser 32 and is provided with a check valve 54 which prevents flow from the condenser into the conduit 52 but not vice versa. A discharge conduit 56 is connected to the upper portion of the condenser 32 and is provided with a check valve which prevents flow backwardly from the conduit 56 to the condenser 32 but not vice versa. The condenser 32, the vapor chamber 30 and the vapor tube 42 are charged with the water to be pumped, and the steam, which is admitted through the flow regulator 40, increases the pressure in the upper portion of the vapor chamber 30 and the tube leg 42b. This pressure increase moves the water and the float 50 downwardly and displaces the water through the bottom of the vapor chamber 30 into the condenser 32 and through the check valve 58 and the conduit 56. When the liquid level in the vapor chamber 30 and the level in the vapor tube leg 42b reach a position at which they are just below the level of the bottom inside bend of the U-shaped tube 42, vapor travels upwardly in the leg 42a causing vapor contact with the top of the condenser and a pressure unbalance is created in the system. This unbalance causes, at first, a gradual flow in the opposite direction (i.e. downwardly in the condenser 32 and upwardly in the vapor chamber 30) to force the steam vapor through the tube 42 and into the condenser, and effect its condensation. The condensation of the steam effects a pressure collapse in the top of the vapor chamber resulting in the quick drawing in of a fresh supply of water through the conduit 36 and the check valve 54 and the return of the float 50 on the water to its original position. Thereafter steam which is admitted in limited quantities through the orifice 40 again builds up in the vapor chamber 30 in sufficient quantity to displace water from the pump again.

It is evident that a significant function of the vapor flow regulator is to prevent vapor from entering the collector at a rate so high as to equal or exceed the rate of transfer of vapor from the collector to the condenser. Otherwise, the pump will be unable to refill and there will be a continuous flow of vapor from the inlet conduit through the collector chamber and U-tube into the condenser.

The thermopump 18 is arranged to take in feed water at somewhat over atmospheric pressure and to discharge it as high as 200 pounds per square inch. The thermopump 20 is arranged to take in feed water around 200 pounds per square inch and discharge it at preferably around five or six times that amount, or, up to 1200 pounds per square inch, depending on the available steam pressure in the boiler 10. A conventional boiler feed pump 22 is provided to raise water from the thermopump 20 at its delivered pressure up to a pressure above the operating pressure of the boiler. Since the boiler steam is utilized to actuate the thermopump 20, of course it would not be possible for this pump to pump the water

to a greater pressure than the boiler without a pressure multiplier or equivalent incorporated with the thermopump.

Besides the function of the thermopumps 18 and 20 to pump water to increased pressures in the boiler system, they are also advantageously used to heat the water which is pumped. The water to be pumped passes through the conduit 52 upwardly through the condenser 32 and out the conduit 56. The condenser 32 is repeatedly being supplied with vapor from the actuating steam which is delivered thereto through the U-shaped vapor tube 42 for condensation therein and in the U-shaped vapor tube 42 during the pumping operation. Thus heat which is repeatedly being supplied to the condenser 32 by the steam is transferred to the pumped liquid as it is circulated through the pump.

A thermopump constructed in accordance with this invention has particular application with boiler systems due to its completely efficient operation. The only heat energy losses are insulation losses, all the heat energy being utilized to either heat the boiler feed water or to pump it to a higher pressure or location. The thermopump may be utilized any place in the system in which the pressure temperature conditions of the available steam and the water to be pumped are such that no boiling of the liquid to be pumped will occur in the pump.

For a pressure in the turbine condenser of around an inch and one-half of mercury the boiling point of water is around 92° F. A thermopump, in order to handle water at such a pressure should be operated at temperatures of at least 20 degrees below this boiling point. A thermopump could be used to replace the conventional condensate pump 16, in those instances in which the water is not close to its boiling point, or where it is desirable to provide cooling for the thermopump condenser 32 or the thermopump vapor tube 42. Such instances would arise, for example, as where it is desirable to preheat fuel oil or lubricating oil and it can be advantageously done by circulating it through the thermopump as mentioned supra. In some circumstances it may be desirable to circulate ordinary cooling tap water through the coils 34 or the heat exchanger 44 in order to cool the condenser 32 and the vapor tube 42, respectively, and take advantage of the attributes of the thermopump constructed in accordance with this invention despite the loss resulting from not using the heat removed by the tap water.

It is possible to use a combination of thermopumps constructed in accordance with this invention to pump liquids, which are at temperatures close to their boiling points, to higher pressures by using a combination of thermopumps as shown in Figure 5. Referring to the vapor pressure curve shown in Figure 4 the line C is the boiling point line for water. It is seen that if it were desirable to pump with a single thermopump, water which was at 14.7 pounds per square inch and approximately 180° F. (point A) to a pressure of 514 pounds per square inch (point B) it would be necessary to change the pressure temperature conditions of the water, which might bring it beyond the boiling point line C (shaded area of the chart), and boil the liquid before it could be raised up to the point B. Boiling of the liquid would prevent condensation of the steam and stop the pump. It is possible, however, by a combination of thermopumps arranged to operate in series to avoid the shaded area of the curve, or conditions which would cause the boiling of the liquid, by raising the pressure of the liquid in steps which would not entail boiling. (See dotted step lines Figure 4.) These steps are chosen to give a large pressure rise with relatively little temperature increase in the first step so that ever greater temperature increases may be taken in latter steps without crossing the boiling point line C.

To accomplish pumping of a liquid which is at or near its boiling point to an increased pressure, three thermo-

pumps D, E and F are connected through a common steam line 60 and individual feeder lines 62, 64 and 66 to a source of actuating steam supply. Each feeder line 62, 64 and 66 is provided with a steam flow regulator or orifice 68 through which actuating steam is admitted to the individual thermopumps. Water within 30 degrees of its boiling point is drawn in through the inlet conduit 70 and check valve 72 to pump D, and is discharged therefrom through check valve 74 and conduit 76 to a pressure accumulator 78. The thermopump D is of such a size and construction that it will pump the liquid to a higher pressure without bringing it within 20 or 30 degrees of its boiling point. (See dotted step line of Figure 4.) The accumulator 78 is provided to act as a reservoir for the liquid and to maintain it at substantially constant pressure during successive discharges of pump D and suctions of pump E.

The pump E takes suction from the accumulator 78 through a conduit 80 and a check valve 82 and discharges through a conduit 84 and a check valve 86 into an accumulator 88 thereby raising the liquid to an additional increase of pressure without bringing the liquid to its boiling point.

Pump F is arranged to take suction from the accumulator 88 through a conduit 90 and check valve 92 and discharge the water through a check valve 94 and conduit 90 to its place of use at the desired increase in pressure without ever having boiled the liquid.

In the arrangement of pumps shown in Figure 1, it is evident that the differential in vapor pressure and temperature which is necessary in order for the pumps to operate at different pressure and temperature levels is obtained by supplying steam vapor to the pump units from different points in the boiler system. In the case of the arrangement shown in Figure 5, wherein the steam vapor is supplied to the pumps from a common point in the system, it will be understood that the pressure level of the actuating steam vapor for each individual pump unit will be regulated by appropriate selection or adjustment of each regulating valve 68.

A boiler system utilizing a thermopump constructed in accordance with this invention will be very efficient in operation. All of the heat energy utilized to actuate the pump is converted either into heat for the liquid being pumped or to pumping energy. The only losses which occur are those resulting from natural insulation losses. A system incorporating the thermopumps of this invention will be reliable and trouble free in operation. The pumps have no major moving parts to wear out and the maintenance of them will be practically nil.

While in accordance with the provisions of the statutes there is illustrated and described herein the best forms of the invention now known, those skilled in the art will understand that changes may be made in the form of apparatus disclosed without departing from the spirit of the invention covered by the claims.

What is claimed is:

1. In a boiler system of the type in which vaporized liquid is delivered from a boiler to a load device such as a turbine or the like, and wherein said vaporized liquid is available at a plurality of points throughout said system at various pressure levels and temperatures, and in which a return line extends from said load device to said boiler to return condensed liquid to said boiler, the improvement which comprises a pumping device connected into said return line as a part thereof and operated by vaporized liquid from said boiler to raise the temperature and pressure of said condensed liquid, said device comprising a vapor collector chamber, a condenser chamber having its lower portion in communication with the lower portion of said vapor collector chamber, a vapor supply conduit connected between the upper portion of said vapor collector chamber and one of said plurality of points in said system, vapor transfer means connected to communicate between the upper

portion of said condenser chamber and the upper portion of said vapor collector chamber, said vapor transfer means having a U-shaped portion extending substantially below the top of said vapor chamber at its intermediate portion, a liquid inlet to said condenser chamber having means therein permitting flow only into said condenser chamber, said return line from said load device being connected to said inlet, a liquid outlet from said condenser chamber having means therein permitting flow only out of said condenser chamber, said return line to said boiler being connected to said liquid outlet, and means in said vapor supply conduit to control the admission of vapor to said vapor chamber, whereby to provide for controlled, cyclical displacement of liquid 10 from said vapor chamber through said liquid outlet, transfer of vapor from said vapor chamber to said condenser chamber through said vapor transfer means to reduce the pressure in said vapor chamber, and inflow of liquid through said liquid inlet.

15 2. The invention defined in claim 1 wherein said means to control the admission of vapor comprises a flow regulating valve.

20 3. The invention defined in claim 1 wherein said vapor chamber and said condenser chamber comprise a centrally disposed vapor chamber and an annular condenser chamber surrounding said vapor chamber, and a liquid conductor disposed within said condenser chamber for conducting a cooling liquid to control condensation in said condenser.

25 30 4. The invention defined in claim 1 including cooling means for controlling vapor condensation in said U-shaped portion of said vapor transfer means, said cooling means comprising a liquid conductor in heat exchange relationship with said U-shaped portion and through which to circulate a cooling liquid.

35 5. The invention defined in claim 4 wherein said liquid conductor comprises a jacket surrounding a section of said U-shaped portion of said vapor transfer means.

40 6. In a vapor actuated pump of the type comprising a vapor collector chamber, a condenser chamber having its lower portion in communication with the lower portion of said vapor chamber, vapor supply means communicating with the upper portion of said vapor chamber, and vapor transfer conduit means comprising a substantially U-shaped vapor tube connected between the upper portion of said vapor chamber and the upper portion of said condenser chamber and extending substantially below the top of said vapor chamber at its intermediate portion, the improvement which comprises means for controlling condensation of vapor in said U-shaped vapor tube, said last-named means comprising a liquid conductor in heat exchange relationship with said vapor tube and through which to supply cooling liquid for controlling vapor condensation in said vapor tube.

45 50 55 7. In a boiler system of the type in which vaporized liquid is delivered from a boiler to a load device such as a turbine or the like, and wherein said vaporized liquid is available at a plurality of points throughout said system at various pressure levels and temperatures, and in which a return line extends from said load device to said boiler to return condensed liquid to said boiler, the improvement which comprises a plurality of pumping devices connected into said return line as serially related portions thereof and operated by vaporized liquid from said boiler to raise the temperature and pressure of said condensed liquid, said devices each comprising a vapor collector chamber, a condenser chamber having its lower portion in communication with the lower portion of said vapor collector chamber, vapor transfer means connected to communicate between the upper portion of said condenser chamber and the upper portion of said vapor collector chamber, said vapor transfer means having a U-shaped portion extending substantially below the top of said vapor chamber at its intermediate portion, a liquid inlet 60 to said condenser chamber having means therein permitting

65 70 75

ting flow only into said condenser chamber, a liquid outlet from said condenser chamber having means therein permitting flow only out of said condenser chamber, a vapor supply conduit connected between the upper portion of each said vapor chamber and a common one of said plurality of points in said system, said return line from said load device being connected to said inlet of the first of said devices in the series, said return line to said boiler being connected to said liquid outlet of the last of said devices in the series, a plurality of pressure accumulators connected one between each successive pair of pumps in the series to receive the discharge of liquid from the previous pump in the series and to deliver liquid for pumping by the next pump in the series, and means in said vapor supply conduit adjacent to each said vapor chamber to control the admission of vapor to each said vapor chamber, whereby to obtain a greater increase in

total pressure and temperature of said liquid than can be obtained in a single such device without causing boiling of said liquid.
